ATTORNEY

UNITED STATES PATENT OFFICE.

GEORGE H. RICKE, OF CINCINNATI, OHIO, ASSIGNOR TO JOHN W. ALLMAN AND AARON MCNEILL, BOTH OF HAMILTON COUNTY, OHIO.

ARCH-SUPPORT.

1,299,615.

Specification of Letters Patent. Patented Apr. 8, 1919.

Application filed August 11, 1917. Serial No. 185,729.

To all whom it may concern:

Be it known that I, GEORGE H. RICKE, a citizen of the United States, residing at Cincinnati, in the county of Hamilton and 5 State of Ohio, have invented certain new and useful Improvements in Arch-Supports, of which the following is a specification.

My invention belongs to that class of arch supports which are inserted into finished 10 shoes. It is a separate article, and not a part of the shoe.

It is a well known fact that a great deal 15 of pain and annoyance is experienced by the users of arch supports in adjusting and adapting the same to the feet, and in many cases the arch supports are discarded for this reason and a different style used in an effort to relieve the foot of its infirmity and find relief. The broken arch is more or 20 less severe and marked in varying cases and the same support will not relieve each case.

A rigid and fixed arch support cannot be 25 used in all cases and with no degree of certainty of relief in any cases. A heavy person will need a stronger and more firm support than a lighter person. A person having a badly broken down arch will need a softer and more yielding support than a person with a slightly broken arch. Feet of varying 30 sizes and of different peculiar formation in their bottoms need arch supports which will fit the peculiar case in each instance.

By using my support the user himself can 35 adjust the arch support to his foot or feet. If he is heavy or light he can readily adjust the support and make it conform to his particular case. If the arch is badly or slightly 40 broken down he can adjust it to fit his requirements. As it is used the person using

the same can make it higher or lower and fit any part of the foot forward and back 45 of the arch, so that the arch will very soon adapt itself to the formation required to give relief and properly support the arch; in other words, I form an arch support which can be manipulated by the user to fit his particular case. It holds the arch up 50 without pain and supports it at the same time.

The various features of my invention and 55 their advantages will readily become apparent from the following specification and claims.

This application is a continuation of my

application filed April 6, 1917, Serial No. 55 160,194, with some changes made therein.

In the accompanying drawings forming part of this specification:

Figure 1, is an inverted view of the arch support all the filler blocks being removed, 60

Fig. 2, is a longitudinal section taken on line 2—2 of Fig. 1, except that the arch support is not inverted and the filler blocks are inserted in position,

Fig. 3, is a bottom view of the spring like arch filler block,

Fig. 4, is a top view thereof,

Fig. 5, is an inverted view of the arch support, all the filler blocks being removed, and

Fig. 6, is a longitudinal section, taken on line 6—6 of Fig. 5, except that the arch support is not inverted and the filler blocks are in position.

Figs. 5 and 6 are a modified form of the 75 arch support.

The arch support is made up of a body part, a series of pockets at both ends and filler blocks or pads distributed as herein-after set forth. In carrying out my invention, I use a body part 1, made of leather or any other desirable material, and which may be of any desired shape or contour. At the heel end I form the pocket 2 and at the toe end I form the pocket 3 of any size and 85 shape desired.

Adjacent to the pocket 2, I place a strip of leather 4, to form another pocket and adjacent to the pocket 3 I place a strip of leather to provide a pocket 5. The pockets 4 and 5 are preferably loose at the inside corners 6—6. The pockets 4 and 5 each extend under the pockets 2 and 3 and are not sewed at their inner extremity, but are 95 open.

In the space 7 I place filler blocks to build up the support. Filler blocks may also be placed in the pockets 2, 3, 4 and 5 to adjust the support to properly fit the foot.

In the space 7, I also place the filler block 8, preferably made of leather or other material of this character. Over the face of this filler block 8 I place spaced spring like strips 9, 9, one being wider than the other. These strips are held in position and connected to the filler block 8 by plates 12, one at each end; staples or cleats as 13 holding the spring strips 9, 9 in position as shown. 100 105

In Fig. 4, one of the plates is shown open at one end before finally connected. In this manner a smooth surface is presented and if one of the strips 9 breaks or becomes worn it can be replaced or heavier or lighter strips can be replaced if necessary, without destroying the filler blocks.

This block 8 is then slipped into space 7 and its ends may pass into the pockets 2 and 10 3 or it may be made shorter.

It will be noticed that in the construction shown in Figs. 1 and 2, flaps 4 and 5 are dispensed with and a strap 15 extends across the space 7 and is sewed at each end thereof 15 to the body part 1 by stitches 20.

I may place any number of filler blocks in this space so as to build the arch support high or lower as needed. In the pockets 2 and 3 I may also place filler blocks as 20 10 and may place as many therein as the particular case may require to properly support the arch. I may leave one or both of the end pockets empty if desired, or fill only one of them.

25 It will be noted that by my construction an arch support can be built up or down to fit any broken arch.

It will readily become obvious that by using my arch support, the user may 30 manipulate the same to fit this particular case, at the time he begins to use it or at any time, during its use in building up the broken

arch. The arch support may be made of any size, material or of any desirable contour, and I may modify the same to some extent, without departing from the spirit of my invention.

What I claim as new and my invention and desire to secure by Letters Patent is:

1. In an arch support, a body portion, 40 pockets disposed at the extreme ends of said body portion, said pockets extending entirely across the body portion to form caps at each end, filler blocks fitting into said pockets, and a filler block with its ends fitting into the two oppositely located pockets.

2. In an arch support, a body portion, 45 pockets disposed at the extreme ends of said body portion, said pockets extending entirely across the body portion to form caps at each 50 end, filler blocks for fitting into said pockets, a strap passing from one pocket to the other, and a filler block formed of suitable material and having spring like strips passing over its 55 face, and plates suitably connected at each end thereof for holding said straps in position.

In testimony whereof I affix my signature in the presence of two witnesses.

GEORGE H. RICKE.
